UNITED STATES PATENT OFFICE

172,744

SWEATER

Violet Giovagnoni, New York, N. Y.

Application February 16, 1954, Serial No. 29,046

Term of patent 3½ years

(Cl. D3—5)

To all whom it may concern:

Be it known that I, Violet Giovagnoni, a citizen of the United States, residing in New York city, in the county of New York and State of New York, have invented a new, original, and ornamental Design for a Sweater, of which the following is a specification, reference being had to the accompanying drawing, forming part thereof.

Fig. 1 is a front view of a sweater, showing my design, and

Fig. 2 is a rear view thereof on a reduced scale.

I claim:

The ornamental design for a sweater, substantially as shown.
